(57) **CLAIM**

The ornamental design for a camera support, as shown and described.

DESCRIPTION

FIG. 1 is a front and right perspective view of a camera support showing our new design;

FIG. 2 is a rear and left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view taken from circle 9 in FIG. 1;

FIG. 10 is a partial enlarged view taken from circle 10 in FIG. 1;

FIG. 11 is a partial enlarged view taken from circle 11 in FIG. 2;

FIG. 12 is a partial enlarged view taken from circle 12 in FIG. 2; and,

FIG. 13 is a front and right perspective view thereof, shown in a shortened state.

The dash-dash broken lines in the drawings depict the portions of the camera support which form no part of the claimed design.

The dot-dash broken lines in the drawings depict the boundaries of the enlarged views that form no part of the claimed design.
